CHARLES LE G. FORTESCUE AND JOHN B. MACNEILL, OF PITTSBURGH, PENNSYLVANIA, ASSIGNORS TO WESTINGHOUSE ELECTRIC & MANUFACTURING COMPANY, A CORPORATION OF PENNSYLVANIA.

CIRCUIT INTERRUPTER.

1,427,368.

Specification of Letters Patent. Patented Aug. 29, 1922.

Application filed October 17, 1918. Serial No. 258,555.

To all whom it may concern:

Be it known that we, CHARLES LE G. FORTESCUE, a subject of the King of Great Britain, and a resident of Pittsburgh, in the county of Allegheny and State of Pennsylvania, and JOHN B. MACNEILL, a citizen of the United States, and a resident of Pittsburgh, in the county of Allegheny and State of Pennsylvania, have invented a new and useful Improvement in Circuit Interrupters, of which the following is a specification.

Our invention relates to circuit interrupters and particularly to high-speed interrupters.

One object of our invention is to provide an actuating electromagnet for an interrupter that shall have means whereby its armature may be quickly and positively actuated from one position to another in anticipation of an overload on the circuit.

Another object of our invention is to provide a circuit-interrupter-actuating device, of the above-indicated character, that shall be simple and inexpensive to construct and effective in its operation.

In practicing our invention, we provide an actuating electromagnet comprising a core member having four arms so disposed as to constitute two magnetic paths severally having an air gap therein. The armature of the magnet is directly connected to the movable member of the interrupter, and the core member is energized from the circuit to cause the armature to normally bridge the air gap in one of the magnetic paths. A winding that is supplied with current directly from the circuit only when the current traversing the circuit changes quickly is disposed around the legs of the core member constituting the other magnetic path for so deflecting the flux through that path that the armature is quickly actuated from the one to the other position without the necessity of opposing the normal magnetic circuit. With this arrangement, the interrupter may be quickly opened in anticipation of an overload on the circuit.

The single figure of the accompanying drawing is a diagrammatic view of a circuit interrupter embodying our invention.

A direct-current circuit 1 is supplied with energy from a source 2 of electromotive force and is provided with a circuit inter-

rupter 3 having an actuating or controlling device 4.

The device 4 comprises a stationary magnetizable core member 5 of substantially hollow rectangular shape having arms 6, 7, 8 and 9 so oppositely disposed with respect to each other and separated by air gaps 10 and 11 as to constitute two magnetic paths for the flux traversing the core member 5. A potential winding 12 is disposed around a portion of the core member 5 and is connected in shunt relation to the circuit 1. The armature 13 of the member 4 is directly connected to the movable members 14 of the interrupter 3 and is adapted to be held in the position shown in the drawing, against the action of a spring 15, when the winding 12 is energized. Windings 16 are disposed around the legs 8 and 9, and the circuit, comprising the windings 16, is connected across a reactor 17 that is connected in series with the circuit 1.

Since the magnetic path comprising the legs 6 and 7 and the armature 13 is of less reluctance than the path comprising the legs 8 and 9, the armature 13 will be held in this position against the action of the spring 15 so long as sufficient potential is maintained on the circuit 1. However, if a short circuit or ground obtains on the circuit 1, the voltage impressed across the reactor 17 will quickly change, and a rush of current will traverse the windings 16. The windings 16 are so disposed with respect to the legs 8 and 9 that the magnetic flux induced by the winding 12 is deflected from the path comprising the legs 6 and 7 to the path comprising the legs 8 and 9, and thus the armature 13 and, consequently, the circuit interrupter 3 will be quickly and positively moved, with the assistance of the spring 15, to its open position, and the armature 13 will bridge the air gap 11 to complete the magnetic circuit through the legs 8 and 9.

Since there is normally an insufficient drop of potential across the reactor 17 to properly energize the windings 16 and, since a relatively great drop of potential will obtain across the reactor 17 before an excessive current traverses the circuit, it will be understood that the windings 16 will be energized substantially in anticipation of an overload on the circuit and, consequently, since the windings 16 are not caused to oppose the

flow of magnetic flux but merely to divert the same from one path to another, the speed of operation of the device 4 is greatly increased to thus ensure effective protection 5 for the circuit 1.

Our invention is not limited to the specific structure illustrated, as it may be variously modified without departing from the spirit and scope of the invention, as set forth in the 10 appended claims.

We claim as our invention:

1. In a circuit interrupter, the combination with a movable contact member, of an actuating electromagnet therefor comprising 15 a core member having two magnetic paths, a shunt winding for energizing the core member, an armature for normally completing the circuit of one magnetic path, and a controlling winding associated with the other 20 path for so energizing the same as to shift the flux thereto and permit the armature to complete the circuit thereof.

2. In an electric circuit, an electromagnet comprising a magnetizable core member having two magnetic paths, a winding for energizing the core member, an armature for normally completing one magnetic path and means energized from the circuit for causing the armature to quickly complete the 30 other magnetic path.

3. An electromagnet for an electric circuit comprising a core member having two magnetic paths, with air gaps therein, means for energizing the core member from the 35 circuit, an armature for normally bridging the air gap in one magnetic path, and means connected to the circuit for causing the armature to bridge the air gap in the other magnetic path when the current traversing the 40 circuit increases quickly.

4. An electromagnet for an electric circuit comprising a core member having two magnetic paths, with air gaps therein, means for energizing the core member from the circuit, 45 an armature for normally bridging the air gap in one magnetic path, and means connected to the circuit for causing the armature to bridge the air gap in the other magnetic path when an overload traverses the 50 circuit.

5. In an electric circuit, the combination with a circuit interrupter, of an actuating electromagnet therefor comprising a magnetizable core having two pairs of oppositely 55 disposed arms, with an air gap therebetween, an armature disposed between the pairs of arms, a potential winding for so energizing the core that the armature normally bridges two of the arms, and a winding disposed 60 around the other arms and operatively connected to the circuit for causing the flux to be so shifted that the armature bridges the other arms when an overload traverses the circuit.

6. In an electric circuit, the combination

with a circuit interrupter, of an actuating electromagnet therefor comprising a magnetizable core having two pairs of oppositely disposed arms, with an air gap therebetween, an armature disposed between the pairs of 70 arms, a potential winding for so energizing the core that the armature normally bridges two of the arms, and a winding disposed around the other arms and operatively connected to the circuit for causing the flux to be so shifted that the armature bridges the other arms in anticipation of an overload on the circuit.

7. In an electric circuit, the combination with a circuit interrupter, of an actuating 80 electromagnet therefor comprising a core member having four arms so disposed as to constitute two magnetic paths having air gaps therein, an armature directly connected to the circuit interrupter, means for so energizing the core member that the armature bridges the air gap in one magnetic path, and means energized from the circuit for so deflecting the flux through the other path that the armature bridges the air gap in 85 that path, under predetermined conditions in the circuit.

8. In an electric circuit, the combination with a circuit interrupter, of an actuating electromagnet therefor comprising a core 95 member having four arms so disposed as to constitute two magnetic paths having air gaps therein, an armature directly connected to the circuit interrupter, means for so energizing the core member that the armature 100 bridges the air gap in one magnetic path, and means for so deflecting the flux through the other path that the armature bridges the air gap in that path in anticipation of an overload on the circuit.

9. In an electric circuit, the combination with a circuit interrupter having a movable member, of an electromagnet comprising a core member having two magnetic paths with air gaps therein, means for energizing 110 the core member from the circuit, an armature for normally bridging the air gap in one magnetic path, and means energized from the circuit for so energizing the other magnetic path as to cause the armature to be 115 moved to bridge the air gap of that magnetic path when an overload traverses the circuit.

10. In an electric circuit, the combination with a circuit interrupter having a movable member, of an electro-magnet comprising 120 a core member having two magnetic paths with air gaps therein, means for energizing the core member from the circuit, an armature for normally bridging the air gap in one magnetic path, and means operatively 125 connected to the circuit for so energizing the other magnetic path as to cause the armature to be moved to bridge the air gap of that magnetic path when an overload traverses the circuit.

11. In an electric circuit, an electromagnet comprising a magnetizable core member having two magnetic paths, a winding for energizing the core member, an armature for normally completing one magnetic path, and a winding for so directly energizing the other magnetic path as to attract the armature thereto.
12. In an electric circuit, an electromagnet comprising a magnetizable core member having two magnetic paths, a winding for energizing the core member, an armature for normally completing one magnetic path, and a winding energized from the circuit for so energizing the other magnetic path as to attract the armature thereto.
13. In an electric circuit, an electromagnet comprising a magnetizable core member having two magnetic paths, a winding for energizing the core member, an armature for normally completing one magnetic path, and a means energized from the circuit and responsive to quick current changes in the circuit for so energizing the other magnetic path as to attract the armature thereto.
14. In an electric circuit, an electromagnet comprising a magnetizable core member having two magnetic paths, a winding for energizing the core member, an armature for normally completing one magnetic path, and a winding energized from the circuit and responsive to quick current changes in the circuit for so energizing the other magnetic path as to attract the armature thereto.
15. In an electric circuit, an electromagnet comprising a magnetizable core member having two magnetic paths, a winding for energizing the core member, an armature for normally completing one magnetic path, and a means energized in anticipation of an overload in the circuit for so energizing the other magnetic path as to attract the armature thereto.
16. In an electric circuit, an electromagnet comprising a magnetizable core member having two magnetic paths, a winding for energizing the core member, an armature for normally completing one magnetic path, and a winding energized in anticipation of an overload in the circuit for so energizing the other magnetic path as to attract the armature thereto.
17. In an electric circuit, an electromagnet comprising a magnetizable core member having two magnetic paths, a winding for energizing the core member, an armature for normally co-operating with one magnetic path, and a magnetic means energized directly from the circuit upon the occurrence of predetermined conditions therein for causing movement of the armature from said path into operative relation to the other path.

In testimony whereof, we have hereunto subscribed our names this 3rd day of Oct., 1918.

CHARLES LE G. FORTESCUE.
JOHN B. MACNEILL.
